UNITED STATES PATENT OFFICE.

J. G. SCHWEMMER AND T. MUELLER, OF PHILADELPHIA, PENNSYLVANIA.

IMPROVEMENT IN FLY-FANS.

Specification forming part of Letters Patent No. 58,683, dated October 9, 1866.

To all whom it may concern:

Be it known that we, JOHN G. SCHWEMMER and THEODORE MUELLER, both of the city of Philadelphia and State of Pennsylvania, have invented a new and useful apparatus for driving off flies and other insects from meat or provisions exposed for sale in market-houses, which apparatus we have termed a "fly-fan;" and we hereby declare the following to be a full and exact description thereof, reference being had to the accompanying drawings, and to the figures and letters of reference marked thereon.

The nature of our invention consists in arranging a series of flaps or brushes proximate to the meat, &c., exposed on hooks or shelves, and in imparting to these flaps a peculiar beating motion, by means of devices hereinafter fully described, for which the required motive force may be obtained from powerful clock-work driven by springs or weights, or from any other convenient source of power.

An important feature of our invention consists in so arranging these flaps relative to their mountings that any one of them may be readily disconnected and removed for the purpose of gaining access to the articles placed behind the same, and afterward be easily replaced.

In order that our said invention may be fully understood, we will now proceed more particularly to describe the same.

Upon reference to the drawings making part of this specification, and in which similar letters of reference allude to like parts throughout the several views, Figure 1 is an elevation of a stall with our improved apparatus attached, the front of the lower part of the stall being removed to represent more clearly the mechanism placed inside. One of the flaps is also detached. Fig. 2 is an end view of the stall and mechanism, and Fig. 3 is an end section thereof.

The flaps A A, secured to long bars a a, can be constructed in various ways. They may consist of a number of cords, strung like fringe upon the bar a. They may be made of broom-corn, or be composed of coarse netting stretched upon a light frame fastened to the bars a.

B B' are bell-cranks, having their fulcrums in brackets C C, projecting from the uprights

D D', which posts form part of the ordinary frame-work of the stall, to which are attached the hooks b b, for suspending the articles for sale. Each set of bell-cranks (of which there are three represented on each post) have their short arms connected by links c c. Their long arms have hook-shaped ends d d, in which are suspended the bars a a of the flaps.

The manner of actuating the bell-cranks, and through them the flaps A A, is as follows: At the side of post D' is provided a vertically-sliding rod, E, guided at both ends in bearings d' d'. This rod has near its upper end a sideward projection, e, and in this is a vertical set-screw, f. The lowest, B', of the three bell-cranks on post D' has its horizontal arm g, Fig. 2, extended beyond the joint of link c, and upon this extension bears the above-mentioned screw f on sliding rod E. This rod has two rectangular bends beneath the table F of the stall, and is above its lower bearing, d', provided with an adjustable arm, h. This arm is actuated by a revolving cam, G, in a manner imparting a downward movement to rod E, which movement is suddenly reversed by a spiral spring, H, at the top when the point of cam G passes the projection i of arm h, on which it bears to depress the rod E. This downward movement of E causes the set-screw f to depress the arm g of bell-crank B' until all the flaps, being connected by links c c, occupy the position shown in Fig. 3.

Upon the described release of the rod E from cam G this movement is reversed, and by means of the tension of spiral spring H the flaps are suddenly thrown back toward the articles from which the insects are to be beaten. These movements are repeated with every revolution of cam G.

The source of power represented in the drawings consists of a strong clock-spring, I, giving motion to the shaft of cam G through a train of wheels and pinions, 1, 2, 3, and 4.

5 is a regulator, driven by wheel 6 and pinion 7, and J is a sliding stop, provided for arresting the motion by sliding it in the direction to bring it in contact with the regulator.

It will be readily seen that any of the flaps A A may be lifted from their respective hooks in the bell-cranks B B', for the purpose of making the articles protected by them readily accessible; but although we have in the above

description explained no other means of accomplishing this object, it must be evident that there are various equivalent means of so doing, one of which would be to suspend the flaps and their mechanism in a frame swinging upon hinges at the side of post D' in such a manner that the whole may be turned about on these hinges to expose the goods without detaching the mechanism in any of its parts.

We do not broadly claim the use of flaps actuated by clock-work or other mechanism for the purpose of keeping off insects; but What we claim as our invention, and desire to secure by Letters Patent, is—

The flaps A A, when operated by the described cam movement through a sliding rod, E, bell-cranks B B', and links e e, and when arranged for the purpose of giving access to the articles thereby protected from insects, substantially as set forth.

JOHN G. SCHWEMMER.
THEODORE MUELLER.
